UNITED STATES PATENT OFFICE

MICHAEL ROMANSKE, OF BOSTON, MASSACHUSETTS

COVER LOCKING AND RELEASING MECHANISM FOR CENTRIFUGAL EXTRACTORS

Application filed March 18, 1929. Serial No. 347,855.

This invention relates to a centrifugal extractor, particularly for laundry use, and comprising a basket rapidly rotated in a case having a hinged cover permitting access to the basket.

The chief object of the invention is to provide improved mechanism for preventing the possibility of injury to the hands of the operator by the rotation of the basket, particularly when the latter is rotating by its own momentum, after it has been disconnected from the source of driving power.

Other objects will hereinafter appear.

Of the accompanying drawings forming a part of this specification,—

Figure 1 is a top plan view of an extractor provided with my improved mechanism.

Figure 2 is a side elevation of the same.

Figure 3 is a view similar to Figure 1, showing a different condition.

Figure 4 shows in elevation, a portion of the mechanism hereinafter described.

Figure 5 is a fragmentary view, showing in section the portion shown by Figure 4, and in elevation portions of the case and cover.

Figures 6 and 6a are fragmentary views showing portions of the detents hereinafter described.

Figures 7 and 8 show in section portions of the flexible rods hereinafter described, and the guides therefor.

Figure 9 shows in perspective two of the flexible rod links.

Figure 10 is a fragmentary view showing in section, the governor hereinafter described, and in elevation a portion of the operating rod.

The same reference characters indicate the same parts in all of the figures.

In the drawings, 12 designates the fixed case of a centrifugal extractor, and 13 designates the usual rotary basket within the case fixed to a vertical basket shaft 14, which is driven by a transmission belt 15, running on a transmission pulley 16, and an idle pulley 17. The pulley 16 is fixed to a power driven counter shaft 18 provided with the usual fast pulley 19, and loose pulley 20, on either of which the driving belt 21 may run, said belt being transferable by a shipper 22

attached to a shipper rod 23, which is movable as usual, in fixed guides, by a shipping lever composed of a hub portion 24, an arm 25 secured to the shipper, and an arm 26 constituting a handle whereby the operator may locate the driving belt on the fast pulley 19, to cause the rotation of the basket, and on the loose pulley 21 to disconnect the basket from the source of power.

The case 12 is provided with a cover 27, connected by a hinge 28 with the top of the case and adapted to be opened and closed by the operator.

I provide the mechanism next described for locking the cover closed and preventing it from being opened by the operator while the basket is being rotated, either by power, or by its own momentum, and for preventing the operator from starting the rotation of the basket while the cover is open.

The cover 27 is provided at diametrically opposite points with ears 29, spaced equally from the hinge 28, and adapted to be engaged simultaneously by detents 31 and 32, to hold the cover closed. Said detents are fixed to the outer ends of flexible rods, each composed of links 33 and 34 (Figures 7, 8 and 9), jointed to each other by pins 35, the rods being adapted to conform to the curvature of arcuate tubular guides 36, fixed to the top of the case. To the inner ends of the flexible rods are attached non-flexible extensions 37, projecting from the guides 36, and connected by links 39 with an arm 40 fixed to an operating rod 41, which is longitudinally movable by the mechanism hereinafter described, to move the flexible rods endwise in the guides 36, and thereby simultaneously engage the detents 31 and 32 with, and disengage them from the cover ears 29, each detent being alternately pushed and pulled, and each being moved in the opposite direction from the other. In this instance the detent 31 is straight and adapted to be projected across one of the cover ears 29, as shown by Figures 1 and 6, by an outward endwise movement of the flexible rod to which it is attached, while the detent 32 is hooked, and adapted to be projected across the other cover ear, as shown by Figures 1 and 6a, by an inward endwise movement of the other

95

100

flexible rod. The arrangement is such that when the operating rod 41 is moved endwise in one direction, the detents 31 and 32 are moved simultaneously in opposite directions into engagement with the cover ears 29, to lock the cover, and when said rod is moved endwise in the opposite direction, the detents are moved simultaneously in opposite directions, out of engagement with the cover ears to unlock the cover.

The operating rod 41 is moved endwise in fixed guides 42 by an angular member designated by 80 and 81, fixed to the shipper lever and so arranged that when said lever is moved to connect the basket with the source of power, the angular member acts to move the rod 41 in the direction required to lock the cover. Said angular member is secured to the hub 24 of the shipper lever by a bolt 82, and has an arm 83 with oppositely disposed ears 84, 84, engaging the edges of the shipper arm 25, so that when the shipper lever is moved to connect the basket with the source of power, the arm 25 will act to move the angular member and cause the arm 81 thereof to engage one end of the rod 41, and move said rod in the direction required to lock the cover. Said rod is maintained in position to lock the cover by automatic means including a centrifugal governor which, when driven by the means presently described, acts to keep the rod in locking position, and is movable by a spring 43 (Figures 1, 3 and 10) which acts to move the operating rod in the direction required to unlock the cover when the power has been disconnected and the governor is at rest.

The governor includes an elongated shaft 44, beside and parallel with the operating rod 41, and journaled in the guides 42, a collar 45, fixed by a pin 46 to the governor shaft 44, a sleeve 47 slideable on the governor shaft, and a plurality of links, each including an outer link 48, pivoted at 49 to the sleeve 45, and provided with a weight 50, and an inner link 51 pivoted at 52 to the outer link, and at 53 to the sleeve 47. To the governor shaft 44 is fixed a friction disk or pulley 54 (Figures 1, 2 and 3), in continuous frictional contact with that portion of the transmission belt 15, which is backed by the pulley 16, so that when said belt is in motion, the governor shaft is rotated.

The sleeve 47 of the governor shaft is connected with the operating rod 41 by a connecting member including a hub portion 56 (Figure 10) interposed between rings 57, fixed to the sleeve 47, and an arm portion 58 clamped between nuts 59 on the operating rod, ball bearings 60 being provided between the hub portion 56 and the rings 57. The movement of the governor links from the full line to the dotted line position shown by Figure 10, causes an endwise movement of the governor sleeve 47 and the operating rod 41 in one direction, said movement being sufficient to

move the detents 31 and 32 to their cover-locking positions.

When the governor links return to the full line position, the spring 43 causes an endwise movement of the governor sleeve and operating rod in the opposite direction, said movement being sufficient to move the detents to their unlocking position.

It will now be seen that when the belt is at rest, the governor is in the condition shown by Figure 1, the cover 27 being unlocked, and that when the belt is in motion, the governor is in the condition shown by Figure 3, and the cover is locked.

To prevent the operator from starting the rotation of the basket when the cover 27 is open, I provide the secondary locking mechanism next described.

Fixed to the cover 27 is an arm 62, to which is pivoted one end of a rod or link 63. The opposite end of said link is pivoted to an arm 64, which is pivoted at 65 to a fixed guide or housing 66, and is provided with a gear segment 67 (Figure 5) meshing with rack teeth 68 on a detent 69, vertically movable in said guide.

The arrangement is such that when the cover 27 is open, as shown by full lines in Figure 5, the upper end of the detent 69 is raised into the path of a projection 71 (Figure 4) fixed to the shipper rod 18, and prevents the movement of said rod required to shift the driving belt 21 from the loose pulley 20 to the fast pulley 19. When the cover is closed, the detent 69 is lowered from the path of the projection 71, and the shipper rod is movable to shift the driving belt to the fast pulley. A spring 70 is interposed between the lower end of the detent 69, and an abutment in the housing 66, to assist in raising the detent when the cover is opened.

I claim:

A centrifugal extractor which includes a rotary basket, a case therefor having a hinged cover, and basket driving mechanism adapted to be started and stopped by an operator, said mechanism including a manually movable lever arm and an operating rod movable endwise in one direction by said arm, and in the opposite direction by governor controlled means; the extractor being characterized by cover locking and releasing means operable by said rod and comprising ears projecting from diametrically opposite portions of the cover, detents simultaneously engageable with said ears to hold the cover closed, and connections between said detents and said operating rod whereby the detents are simultaneously engaged with the cover ears, and disengaged therefrom by endwise movements of the operating rod.

In testimony whereof I have affixed my signature.

MICHAEL ROMANSKE.
